UNITED STATES PATENT OFFICE.

OTTO G. PFEIFFER, OF SALT LAKE CITY, UTAH, ASSIGNEE, BY MESNE ASSIGNMENTS, TO
ST. LOUIS WASHING MACHINE COMPANY, A CORPORATION OF ILLINOIS.

WASHING-MACHINE.

1,268,784.

Specification of Letters Patent.

Patented June 4, 1918.

Application filed December 27, 1911. Serial No. 668,184.

To all whom it may concern:

Be it known that I, Otto G. PFEIFFER, a citizen of the United States, and residing at Salt Lake City, in the county of Salt Lake and State of Utah, have invented certain new and useful Improvements in Washing-Machines, of which the following is a specification.

This invention relates to washing machines, and more particularly to washing machines of the power driven type.

One of the objects of this invention is to construct a washing machine which will be simple in its construction and operation, cheap to manufacture, and possess great strength and durability consistent with lightness in weight.

Another object is to construct a washing machine in which the casing or container is a self-contained structure supported between end frames or standards, and in which the driving mechanism and drum bearings are supported on and carried by these end frames.

Another object is to support this drum in bearings which can be easily rendered watertight and be at the same time accessible; and to construct the parts so that the drum is removable and replaceable at pleasure, and so that the opening and closing of the casing or container will release and lock the drum in position, whereby when the casing is closed the drum will be retained in position; and whereby when the casing is opened the drum will be released so as to permit its removal from the casing.

Further objects will appear from the detail description taken in connection with the accompanying drawings in which:

Figure 1 is an end elevation of the complete washing machine embodying this invention,

Fig. 2 is a front elevation,

Fig. 3 is a section on the line 3--3 Fig. 1,

Fig. 4 is a section on the line 4--4 Fig. 2,

Fig. 15, Fig. 18 is a detail section of the drum 70
body.

The machine body or casing.—Referring to the accompanying drawings, 25 and 26 designate a pair of end frames of skeleton construction and having integral therewith legs 27. The end frame 25 has an integral cross member 28 forming supporting means for one of the drum bearings and the driving gearing, and the end frame 26 is also provided with a cross member 29 for supporting the other drum bearing. These end frames are provided with annular flanges 30 and annular recesses 31. The end frames form the frame work of the supporting brackets for the casing body, and are preferably malleable castings so as to constitute a light skeleton frame work. The casing proper is constructed of sheet metal and comprises a casing body 32 and casing ends 33 and 34. The casing body and ends are 90
secured together by outwardly folded seams 35, leaving the interior of the casing entirely smooth. After the casing has been seamed, the whole is tinned or galvanized so as to thoroughly close all seams. The casing so 95
constructed forms a self contained structure which is supported at its ends by the flanges 30 of the end frames, with the seams 35 lying in the recesses 31. The assembled casing and end frames are clamped and secured 100
together by rods 36, 36, 37 and 38, these rods passing outside of the casing walls and being secured in place by nuts as shown in the drawings. The ends of the casing body are bent around the rods 37 and 38 105
as shown in Figs. 4, 6 and 7 so as to leave an open space which is closed by a cover hereafter described, and so as to leave the

ends or edges of the opening smooth. The rod 38 passes through lugs 39 on the end frames, and the flanges 30 are recessed as shown at 40 to permit the bent end of the 5 casing to lie therein. A drain pipe 41 is riveted to the bottom of the casing body as shown in Fig. 5, and this drain pipe extends through the end frame 26 and is provided at its end with a cap 42. The end frames 10 have formed thereon lugs 43 and 44 adapted to support a beam 45. This beam is bolted to and connects the end frames and forms a support for the wringer which is generally indicated at 46.

15 The machine frame or casing thus comprises a pair of cast skeleton end frames supporting a self contained sheet metal casing or container. The parts are connected and clamped together and braced by means 20 of the rods and the wringer beam so as to form together a braced structure which is strong and rigid and at the same time of light weight. The seams are so formed that they will form a tight joint without the use 25 of solder, and these seams are thoroughly protected and inclosed by the recesses in the end frames. The construction of the seams leaves the interior of the casing entirely smooth.

30 *The drum or movable member.*—Referring to Figs. 3 and 14 to 18 inclusive, 50 and 51 designate two end frames forming the ends of a drum. These end frames are of skeleton construction and preferably malleable castings. Each of the end frames is provided with an annular flange 52 and with a series of radially extending lugs 53 (in this case four) projecting inwardly. The ends 54 and the body 55 are constructed of 35 sheet metal. The body is made of a single piece of sheet metal bent reentrantly as shown in the drawings to form inwardly extending projections or ribs 56. The end frames are connected and secured together 40 by means of rods 57 riveted at their ends to the end frames and constructed to firmly clamp the parts together. The ends of the body 55 are turned over rods 58 connecting and secured to the end frames so as to form 45 an opening in the drum, which opening is closed by a suitable cover 59. The reentrant projections 56 pass over and around the lugs 53 and the rods 57, so that the rods 57 will lie inside of these projections and outside of 50 the interior surface of the drum. The cover 59 is movably and removably secured to the drum by means of straps 60 engaging slots 61 in the casing body. The cover and the drum body are provided with straps 62 and 55 63 bent to form eyes for a latch bolt 64 having a handle 65. This latch bolt is provided with a projection 66 adapted to engage the right hand strap 63 when the bolt is moved to unlocking position, so as to prevent 60 the inadvertent complete disengagement of the bolt from the strap 62. The drum body is provided with a series of holes 67 so as to permit the water in the casing to enter the drum. The metal around the holes is struck up as shown in the drawings 70 so that it will project outwardly beyond the outside surface of the drum, thereby forming in effect small tubes projecting from the drum. The end frames are provided with lugs or trunnions 68 to support 75 the drum in its bearings as hereinafter described. After the parts are clamped together the whole structure is tinned or galvanized, whereby the parts will be firmly secured together without the necessity of 80 soldered joints.

It will be seen that the drum is composed entirely of metal, the end frames being malleable castings, and the body and ends proper of sheet metal. These parts are secured and clamped together by rods connecting and bracing and clamping the elements of the drum together into a rigid structure having great strength compared to its weight. The inwardly extending projections 56 formed by bending the body, not only strengthen the drum, but also form a 85 corrugated inner surface for elevating the clothes in the drum. Since the ends of the drum body are bent around the rods 58, and 90 since the projecting portions 56 are bent around the rods 57, the interior of the drum will be left entirely smooth, leaving no sharp edges or projecting points upon which the clothes can catch. It is found that the 95 peculiar construction of the flanged apertures will promote the washing operation, since these projections will not only draw air, but also water and steam into the drum as the drum rotates.

105 *The drum bearings and retaining means.*—Referring to Figs. 3, 4, and 8 to 13 inclusive, 70 and 71 designate a pair of brackets located inside of the casing and riveted to the cross bars 28 and 29 respectively of the end 110 frames. Each of these brackets is provided with an inwardly projecting bearing 72 for supporting the trunnions 68 and 69 of the drum. These bearings are constructed as shown in the drawings so as to permit the 115 drum to be removed from and replaced therein. In order to permit such removal the trunnion 69 is provided with an angular portion 73 adapted to engage a similar recess or slot in the end of the drum shaft 74. 120 With this construction therefore the drum can be removed from the casing when the angular portion 73 is in a vertical position as shown in Fig. 12. Means are however provided for retaining or locking the drum in 125 its bearings while the machine is in operation, and this means is connected with the cover so that when the cover is closed the drum will be retained or locked in position, and when the cover is open the drum will be 130

released so as to permit its removal from the casing. This retaining means will now be described.

A pair of brackets comprising each an arcuate rim 75 and radial arms 76 are arranged to be movably supported on the bearings 72. For this purpose each of the brackets is provided with a bearing embracing member 77 partially embracing the bearing 10 so as to leave an open space as shown in Figs. 4 and 8. It will be understood that the outside face of the bearing 72 is machined so as to furnish a bearing surface for the member 77. Each of the brackets is 15 provided with a laterally extending flange 78 and with laterally extending extensions 79 opposite the arms 76. The cover body 80 is constructed of sheet metal, and the ends of this cover are riveted to the flanges 78 20 and the extensions 79. The ends of the cover are provided with operating handles 81, and the casing ends have riveted thereto stops 82 and 83 for locating and limiting the cover in open and closed position.

It will be noted that the bearings for the drum are located entirely inside of the sheet metal casing, but that these bearings are supported directly from the cross bars of the end frames. This construction not only 25 permits efficient packing of the bearings and therefore prevents leakage; but furnishes also a strong and rigid support for the drum, since the drum is supported from the end frames and not from the sheet metal 30 body.

The cover comprises a frame work supporting a sheet metal body and this frame work and body are secured together so as to form a braced structure having considerable rigidity compared with its weight. This is especially brought about by the 35 flange construction having the inwardly extending projections or braces 79 opposite the arms. The cover is supported upon well defined bearings, thereby permitting free 40 movement of the cover and keeping this cover in effective alignment with the casing, thereby preventing sticking or binding.

When the cover is in the position shown 45 in full lines in Fig. 4 and in Fig. 8, the openings in the bearings 72 will be bridged over by the bearing members 77 connected to the cover. This will lock the drum in position in its bearings, as it will prevent 50 the removal of the trunnions. When however the cover is in the position shown in dotted lines in Fig. 4 and in Fig. 12, then the open portion of the bearing member 77 will be opposite the openings in the 55 bearings 72, so that the trunnions may at this time be removed from their bearings. It will therefore be seen that when the cover 60 is in closed position the drum bearings will be bridged over so that the drum will be retained or locked in its bearings, while when

the cover is in open position the drum bearings will be unbridged so that the drum may at this time be removed from its bearings and from the casing. This invention therefore provides means connected with the 70 cover, whereby when the cover is closed the drum will be retained in operative position, and whereby when the cover is open the drum will be released so as to permit its removal from the casing. This is a 75 very convenient arrangement. The operator need not remember to lock the drum in position, since this is necessarily accomplished by closing the cover, which latter operation is always performed prior to the 80 starting of the machine. As soon as the cover is opened the drum is in condition for removal.

The casing or container comprises sides and ends secured together to form an independent self-contained structure or unit 85 in which the joints are formed independent of the end frames or standards. This self-contained casing is in turn supported in and between the end frames; these end frames 90 do not, however, form or close the joints in the casing, but the joints are formed wholly in the casing itself. This construction will therefore withstand the rough usage and the twisting strains to which machines of this type are usually subjected. The drum and the wringer, as well as the 95 driving gearing therefor are carried on and supported directly by the end frames and entirely independent of the casing. This 100 results in a construction having not only great strength, but since the stresses due to the weight and leverage of the gearing are transmitted directly to the end frames and not to the casing, the casing will hold its 105 shape and the joints of this casing will not be opened.

It is obvious that various changes may be made in the details of construction without departing from this invention, and it is 110 therefore to be understood that this invention is not to be limited to the specific construction shown and described.

Having thus described the invention what is claimed is:

1. In a washing machine, a casing, a drum 115 removably mounted therein, a movable cover for said casing extending above, and arranged to swing about the axis of, said drum, and means movable with and operable upon opening and closing of said cover for releasing and retaining said drum.

2. In a washing machine, a casing, a drum 120 therein, a movable cover for said casing arranged to swing about the axis of said drum, bearings projecting into said casing and adapted to removably sustain said drum therein, and means for locking said drum in its bearings, said means being connected with and movable with said cover. 130

3. In a washing machine, a casing, a drum therein, a movable cover for said casing arranged to swing about the axis of said drum, bearings for removably sustaining said drum in said casing, locking means movable over said bearings for locking said drum in said bearings, and means connecting said locking means with said cover so as to move therewith.
- 10 4. In a washing machine, a casing, a drum therein, a movable cover for said casing arranged to swing about the axis of said drum, bearings for removably sustaining said drum in said casing, locking means adapted to embrace said bearings and lock said drum in said bearings, and means connecting said locking means with said cover so as to move therewith.
- 15 5. In a washing machine, a casing, a cover for said casing, a drum in said casing, bearings for removably sustaining said drum in said casing, means supported by said casing for driving said drum, said driving means having a removable connection with said drum, and means operatively connected with said cover constructed to lock said drum in said bearings and in engagement with said driving means.
- 20 6. In a washing machine, a casing, a cover for said casing, a drum in said casing, bearings for removably sustaining said drum in said casing, a driving shaft having a con-
- nection with said drum constructed to permit the removal of said drum from said casing, and means adapted to embrace said 35 bearings and operatively connected with said cover constructed to lock said drum in said bearings and in engagement with said driving means.
7. In a washing machine, a casing, a cover 40 for said casing, a drum in said casing, bearings for supporting said drum at its ends in said casing, means for supporting said cover on said bearings to permit it to move to open and closed positions, and means on said 45 cover supporting means for retaining said drum in position.
8. In a washing machine, a supporting structure comprising a pair of end frames forming supporting brackets, a casing comprising sides and ends secured together to form a self-contained structure and supported in said end frames, a drum in said casing, bearings mounted on said end frames and adapted to removably support said 50 drum, and a cover for said casing journaled on said bearings and having means for retaining said drum in its bearings.

In testimony whereof I affix my signature in presence of two witnesses.

OTTO G. PFEIFFER.
